UNITED STATES PATENT OFFICE.

JULES VANPETEGHEM, OF GHENT, BELGIUM.

DEVICE FOR LOADING COPS ON SPINDLES.

SPECIFICATION forming part of Letters Patent No. 739,952, dated September 29, 1903.

Application filed November 24, 1900. Serial No. 37,651. (No model)

To all whom it may concern:

Be it known that I, JULES VANPETEGHEM, a subject of the King of Belgium, and a resident of 14 Rue de la Coriandre, Ghent, Belgium, have invented certain new and useful Devices for Loading Cops on Spindles, of which the following is a specification.

This invention relates to an improvement in preparing bobbins and fixing them in shuttles and is designed to lessen the labor of the weaver and to preserve his health. At the same time the stoppages of the loom are diminished and its producing capacity is correspondingly increased.

In the system of working hitherto in use the bobbins are handed to the weaver, who then fixes them in the shuttles. In doing so he must not only properly fix the bobbin in place, but must compress the cop, so as to attain a certain amount of adhesion between the layers of thread, sufficient to enable the bobbin to support without deformation the numerous and violent shocks to which it is submitted during its course through the loom, for such deformation causes bad unwinding and frequently wrecks the bobbin. Accordingly to fix the cop on the spindle of the shuttle the workman usually manually forces the cop onto the spindle with all his force, and as a good weaver is not necessarily a muscular man a large proportion of the bobbins are badly prepared. Again, every time the shuttle has to be refilled or the thread breaks the loom has to be stopped, causing a loss of time, which may amount to from thirty-five to forty per cent. where there are many wefts. By the present invention this loss of time is much diminished because the faulty unwinding and consequent breakages are avoided and the shuttles contain

nearly twice as much thread as is usually the case, so that stoppages for refilling are reduced. For this purpose the cop is fixed and compressed mechanically on the spindle. When the cop is placed on the spindle, it descends nearly to the bottom thereof. It is then submitted to pressure, which at the same time fixes it on the spindle and compresses it in the direction of the axis of the spindle to such an extent that the shuttle can contain nearly twice as much thread as was formerly the case. For facilitating the refilling of the

shuttle the spindle is specially constructed, so that it may be easily introduced into and removed from the shuttle.

The accompanying drawings show the last-named improvement and a machine suitable for compressing the cops.

Figure 1 is a side elevation of the lower end of the bobbin. Figs. 2 and 3 are longitudinal sections of the shuttle, showing how the bobbin is fixed in place. Fig. 4 is a side elevation of the apparatus for compressing the cop. Fig. 5 is a front elevation of the same, while Fig. 6 is a special form of spindle, the purpose of which will be explained.

The shuttle is made in two pieces—that is to say, the spindle is independent of the shuttle, and in order that the former may readily be placed in and removed from the latter it has a notch *a* at its lower end, which in inserting the bobbin into the shuttle takes over a pin *d*, so that the extreme end *b* of the spindle can be introduced between this pin and the spring *c*. The bobbin is then turned on the pin *d* until it lies in the shuttle, as is commonly the case. To facilitate the introduction of the end *b*, the base of the spindle is sloped, as shown at *e e*, Fig. 1. When the bobbin is placed in the shuttle, as shown in Fig. 3, it is fixed therein in the manner usually adopted for fixing bobbins in shuttles.

The apparatus for fixing and compressing the cops on the spindles is shown in Figs. 4 and 5 and is constructed as follows: A is the frame. B is the starting-lever, carrying the pawl *C* and centered at *B'*. D is a ratchet-wheel keyed to the shaft *U* and having a part *D'* without teeth. *E* is a lever centered on *U* and carrying at one end the pawl *F* and connected at the other end by a link *G* with a crank *H* on a shaft *I*, which is intermittently revolved. *J* is a hollow cone lined with coarse felt or cloth and of an internal angle corresponding with that of the head of the bobbin onto which it is to be placed in order to compress the cop *L* on the spindle *O*. *K* is a sliding piece and carries the cone *J* and an arm *X*. *M* is a rod attached at its lower end to a crank *S* on the shaft *U* and at its upper end to the arm *X* through the spring *N*. *Q* is a spring which serves to raise the lever *B*. *T* is a support for the spindle *O* and is pref-

erably in the form of a clamp, in which the end of the spindle can be held by the screw V. W is the bearing of the shaft U.

As already said, one of the chief advantages 5 of this invention is that the shuttle is made to hold nearly double the quantity of thread held by ordinary shuttles. While this is achieved by compressing the cops, it is obvious that the spindles must have the ordinary 10 length to fit the shuttles. The length of the cop before compression, however, is nearly double that of the spindle, as is represented in dotted lines in Figs. 4 and 5, so that it is necessary to use a temporary spindle 15 nearly double the length of that which is to carry the cop in the shuttle. For this purpose there is fitted over the upper end of the permanent spindle O a socket on the lower end of a supplementary slightly-coned spindle O'. (Shown in dotted lines in Figs. 4 and 5 and on a larger scale in Fig. 6.) The joint spindle O O' thus produced is the length of the uncompressed cop and is fixed in the support T by means of the notch a in the permanent spindle O and by means of the screw V. 20 This mode of temporarily lengthening the spindle is only one of several.

The apparatus works as follows: The shaft I rotates intermittently and oscillates the lever E on the shaft U. When the pawl F, carried by the upper end of lever E, is resting on the part D' of the ratchet-wheel D, the oscillation of the lever E has no effect upon the said ratchet. Fig. 4 therefore shows the apparatus at rest. To put it into action, the lever B must be depressed, so that the pawl C may turn the ratchet-wheel D in the direction of the arrow until the pawl F engages with a tooth, enabling the oscillation of the lever E to rotate the ratchet. The lever B is then allowed to resume its former position, 25

45 into which it is lifted by the tension of the spring Q, while the ratchet D continues to rotate, carrying with it the crank S, which reciprocates the rod M. Thus at every revolution the cone J is pulled down onto the bobbin to compress the cop and is raised again to its former position. When the revolution of the ratchet-wheel is nearly completed, the pawl has once more arrived at the mutilated 50 part D' and the apparatus comes to rest. The spring N is provided lest the pressure of the cone on the bobbin should become excessive, in which case the spring will extend.

55 The mechanism described is merely an illustration of the kind necessary for carrying out the system, and other combinations for effecting the same purpose may be substituted for the one shown.

Having thus described the nature of this invention and the best means I know for carrying the same into practical effect, what I claim is—

An apparatus for compressing cops on their spindles, consisting of a hollow cone J, a sliding piece K carrying the same, a rod M controlling said sliding piece, a shaft U, a crank thereon connected with said rod M, a ratchet-wheel fast on said shaft having a portion without teeth, an oscillating lever E mounted 65 freely on the shaft, a pawl carried by said lever coöperating with the ratchet-wheel, means for oscillating said lever, and means for initially moving the ratchet-wheel to make the same responsive to the action of the pawl, substantially as described. 70

In witness whereof I have hereunto set my hand in presence of two witnesses.

JULES VANPETEGHIEM.
